UNITED STATES PATENT OFFICE.

LEE W. MELCHER, OF LA CROSSE, WISCONSIN, ASSIGNOR TO LA CROSSE TRACTOR CO., OF LA CROSSE, WISCONSIN, A CORPORATION OF DELAWARE.

TRACTOR ENGINE.

Application filed March 9, 1916. Serial No. 83,107.

To all whom it may concern:

Be it known that I, LEE W. MELCHER, a resident of La Crosse, in the county of La Crosse and State of Wisconsin, have invented certain new and useful Improvements in Tractor Engines, of which the following is a full, clear, and exact description.

This invention relates to tractors.

The object of the invention is to improve the frame construction, so as to afford a strong and durable structure upon which the engine proper and other working parts can be suitably attached, and give a mechanism of sufficient strength at the place of maximum stress, and be comparatively light and secure in construction.

Another object of the invention is to provide a main structure carrying the heavy portion of the load and an extension therefrom in tubular form for carrying a guide wheel, with means of clamping the tube to the main structure to prevent rotation of the tube with relation to the main structure.

Another object of the invention is to provide a main frame with a tubular strut extending transversely of the structure, with engine sustaining brackets integral with the strut and extending angularly to the direction thereof, with means for attaching wheel axles thereto whereby the main stress of the frame is carried upon the strut.

In the drawings: Fig. 1 is a plan view of the main frame of the structure. Fig. 2 is a rear view of the main frame. Fig. 3 is a side elevation of the right forward end of the main frame with a portion broken away to show the method of holding the tubular extension against rotation. Fig. 4 is a cross section of the tubular portion of the main frame on the line *e*—*e* of Fig. 1 with a draw bar and seat bracket attached thereto. Fig. 5 is a detail view of the right side of the frame on the line *b*—*b* and *g*—*g* of Fig. 1 and showing the method of attaching a stub axle above the tubular strut of the frame, with portions of the front and rear engine sustaining brackets. Fig. 6 is a detail on the line *d*—*d* of Fig. 1, showing the rear engine bracket, and a sub-bracket for sustaining the transverse engine-driven shaft. Fig. 7 is a detail on the line *h*—*h* of Fig. 1, showing a rear view of the right forward end of the main frame and a rear end view of the extension tube. Fig. 8 is a left side-elevation, showing the left front brackets for sus-

taining the transverse engine-driven shaft and the front and rear brackets for sustaining a shield for covering the left drive wheel, with the tubular strut shown in section across the bolt holes 11^a. Fig. 9 is a detail of the forward engine supporting bracket, on the lines *c*—*c*. Fig. 10 is an elevation of the right hand side of the assembled structure, showing exhaust pipes leading from the engine to the tubular extension, and having portions broken away. The right hand driven wheel is omitted from this view for the sake of clearness in showing the relation of the parts. Fig. 11 is a detail of the method for connecting the exhaust pipes to the tubular extension.

1^a indicates a main frame, having a main sustaining portion in the form of a tubular strut, 1, extending transversely of the frame. 2 indicates a bracket extending rearwardly and upwardly from the right hand portion of the strut provided with bosses having bolt holes 8^a and a shelf portion 2^a. 3 indicates a bracket integral with and extending forwardly from the strut with vertical and horizontal portions 3^b and 3^c. 3^a is a vertical rib extending over the right longitudinal member of 3 for strengthening the bracket 6^a carrying the right hand boxing for the transverse shaft, having the holes 6^b for securing the under-half box. See Figs. 1, 3 and 5. 3^e is an angular brace on bracket 3 for strengthening the same. 4 is an integral bracket formed on the rear right end of the tubular strut 1, carrying the rear bracket 9 for sustaining the rear end of a shield for covering the right carrying wheel. 5 is a bracket integrally attached to the forward side of the left end of the strut 1, carrying the left box 6 for the transverse shaft, the latter being provided with the clamping bolt holes 6^b. 7 is a sub-bracket attached to the left forward portion of the bracket 3, and carrying the center box 7^a for the transverse shaft 6^a. 8 indicates a forward engine carrying sub-bracket springing from the central forward portion of the bracket 3, provided with strengthening ribs 8^b and with clamping bolt holes 8^a. 9 indicates the front and rear brackets for sustaining the right hand shield for the right wheel, the forward bracket being sustained upon the right hand shaft bracket 6^a and strengthened by the rib 9^a. 10 indicates a forward shield bracket sustained on the left boxing bracket 6 and 110

- 10^a a rear shield sustaining bracket mounted on the rear bracket 6^e formed on the strut 1. 11 and 11^a indicate holes through the strut for bolts clamping the stub axle 19 to the strut.
- 5 12 indicates a self centering bearing block upon which the stub axles 19 are sustained, one of these bearing blocks 12 being placed between each of the rear and forward holes 11 and 11^a. 13 indicates holes in the bottom 10 of the strut as shown in the detail of Fig. 4 for attaching the central draw-bar by means of bolts and nuts 13^a.
- 14 is a sub-bracket attached to the forward right hand corner of the bracket 3, in 15 form, to coincide with the outer surface of the tubular extension 15, and provided with clamping bolt holes 16 for securely attaching the tubular extension to the bracket 14 by means of the **U** bolts 16^a, as 20 shown in Fig. 7. 17 is a downwardly projecting lug formed on the under surface of the curved bracket 14 and fitting within an orifice in the tube 15 for preventing a transversely rotative movement of the tube 15 25 relation to the frame. See Figs. 1, 3 and 7.
- 20 indicates a draw-bar attached to the central portion of the strut by means of bolts and nuts 13^a through the bolt holes 13, as indicated in Fig. 4, provided on its upper surface 30 with a bracket 21, having bolt holes 22 for attaching a seat spring and seat. At its rear end the hole 23 is provided for receiving a clevis for the attachment of a plow or other structure to be drawn by the tractor.
- 35 Rigidly attached to each of the extremities of the transverse shaft 6^a is a pinion 24 shown in section only in Fig. 10, having teeth meshing in gearings 25, attached toward the peripheries of the sustaining and driven wheels 26, in which at either side of the structure are mounted the stub axles 19, the stub axles being the means by which the frame portion of the structure is sustained in the wheels.
- 40 45 indicates a radiator attached intermediate of the length of the tubular extension 15, by means of the clamping bolt 28, and properly connected to the engine.
- 50 A and A¹ indicate an opposed cylinder engine mounted on the forward and rear brackets 8 and 2 and properly clamped through the bolt holes 8^a.
- 55 A² indicates the exhaust chambers of the engine to which are attached exhaust pipes A³ leading therefrom to a common chamber A⁴, inserted in the rear of the tube 15 below the bracket 14 and held therein by pins A⁵.
- 60 29 indicates a front steering wheel bracket rigidly clamped to the forward end of the tubular extension 15 by the **U** bolts 30 and carrying at its forward upper end a socket 31 in which is mounted the circular shank of a fork 32, in which is rotatively mounted the front steering-wheel 33. Above the 65 socket 31 and on the shank of fork 32 is at- tached a section of a worm-wheel 34, gearing with worm 35, which is rigidly affixed to the rod 36, extending backwardly and provided with a hand wheel not shown, the rear end of the rod 36 being sustained in a bracket 37 70 suitably attached to the shelf 2^a on bracket 2 shown in Figs. 1 and 10.
- It is manifest from the above description that the structure described will give a maximum of strength with a minimum of 75 weight and material, and a structure that is compact, readily accessible, and very little liable to breakage.
- It is to be understood that while my invention is embodied in the structure shown 80 and described herein, its scope is not limited to the precise structure shown and described.
- Having described my invention what I claim is:
1. In a tractor, the combination with sustaining wheels, of a main frame provided with integral means, an engine comprising a crank case separately formed from the frame and secured to said means, said main frame having a transverse tubular strut 85 outside of the engine, and a wheel axle sustained on the outside of said strut.
  2. In a tractor, the combination with sustaining wheels, of a main frame provided with integral means, an engine comprising 90 a crank case separately formed from the frame and secured to said means, said main frame having a transverse tubular strut outside of the engine, a wheel axle outside of said strut, and a removable connection 95 between said strut and the axle.
  3. In a tractor, the combination of sustaining wheels, with a main frame comprising a transverse tubular strut supported in the wheels, means for securing an engine to 100 the strut comprising longitudinally extending brackets integrally secured to the strut, an engine, and a driving connection between the engine and the wheels.
  4. In a tractor, the combination of sus- 110 taining wheels, with a main frame comprising a transverse tubular strut supported in the wheels, means for supporting an engine on the strut comprising longitudinally extending brackets integrally secured to the 115 strut, said brackets being in angular form in cross section.
  5. In a tractor, the combination of sus- 120 taining wheels, with a main frame comprising a transverse tubular strut supported in the wheels, engine sustaining brackets integrally attached to the strut, a longitudinally extending tubular member carrying a steering wheel, a bracket on the strut for securing the tubular member to the strut, 125 means for securing the tube to the bracket, and a lug on the bracket for holding the tube against rotative movement.
  6. In a tractor, the combination of sus- 130 taining wheels, with a main frame compris-

- ing a transverse tubular strut supported in the wheels, a bracket extending longitudinally from the strut, a longitudinally extending tubular member, means for securing 5 the tube to the bracket comprising **U** bolts, and means comprising a lug for securing the tubular member against rotative movement.
7. In a tractor, the combination with sustaining wheels, of a main frame provided 10 with integral means, an engine comprising a crank case separately formed from the frame and secured to said means, said main frame comprising a transverse tubular strut outside of the engine, a wheel axle connected to the outside of the strut, and integral means on the strut for rigidly securing thereto a draw bar for pulling a separate vehicle.
8. In a tractor, the combination with sustaining wheels, of a main frame provided 20 with integral means, an engine comprising a crank case separately formed from the frame and secured to said means, said main frame having a transverse tubular strut outside of the engine, a wheel axle connected to the outside of said strut, a draw bar for pulling a separate vehicle secured to the strut, and means on the draw bar for sustaining a seat.
- 30 9. In a tractor, the combination of sustaining wheels, with a main frame comprising a transverse tubular strut supported in the wheels, a bracket extending longitudinally from the strut, a longitudinally extending tubular member, means for securing 35 the tube to the bracket comprising **U** bolts, and means comprising a lug on the bracket and an orifice in the tubular member to secure the tubular member against rotative movement.
- 40 10. In a tractor, the combination of sustaining wheels, with a main frame comprising a transverse tubular strut sustained in the wheels, a main bracket on the strut extending substantially at right angles to the 45 strut and having diagonal braces on one side thereof connecting the bracket with the strut.
- 50 11. In a tractor, the combination of sustaining wheels, with a main frame comprising a transverse tubular strut sustained in the wheels, means for sustaining an engine on the strut comprising a rearwardly extending bracket on the strut, and a for- wardly extending bracket on the strut comprising 55 a main bracket, sub-brackets formed on the main bracket and diagonal bracing portions between the main bracket and the strut.
12. In a tractor, the combination of sus- taining wheels, with a main frame comprising 60 a transverse tubular strut sustained in the wheels, means for sustaining an engine on the strut, comprising rearwardly and for- wardly extending brackets formed integral- 65 ly with the strut, the forward bracket comprising a main portion and sub-brackets formed thereon and diagonal bracing portions between the main bracket and the strut.
13. In a tractor, the combination of sus- 70 taining wheels, with a main frame comprising a transverse tubular strut sustained in the wheels, means for sustaining an engine on the strut comprising rearwardly and forwardly extending brackets formed integral- 75 ly with the strut, the forward bracket comprising a main portion and sub-brackets formed thereon, diagonal bracing portions between the main bracket and the strut, and a longitudinal tubular extension rigidly se- 80 cured to one of the sub-brackets.
14. In a tractor, the combination of carry- 85 ing wheels, with a main frame comprising a transverse strut, a plurality of brackets extending longitudinally from the strut, a sub-bracket on one of the brackets, a longitudinal extension carrying a steering wheel and means for rigidly attaching the exten- sion to the sub-bracket.
15. The combination of traction wheels, a 90 rigid frame, means for supporting the frame by the traction wheels, a tubular arm hav- 95 ing its rear end rigidly secured to said frame and projecting forward therefrom, a steering wheel connected with and support- ing the forward part of said arm, an ex- plosive engine mounted upon said frame and comprising a plurality of cylinders and pipes for conducting the exhaust separately from the cylinders of the engine respec- 100 tively to one end of said arm so the exhaust from the cylinders will be separately conducted to the arm.

LEE W. MELCHER.
